G. T. CHERINGTON,
FRAME FOR PHONOGRAPH MOTORS.
APPLICATION FILED APR. 9, 1920.

1,391,717.

Patented Sept. 27, 1921.

Inventor,

George T. Cherington
BY Dodson & Roe Attorneys.

UNITED STATES PATENT OFFICE.

GEORGE T. CHERINGTON, OF WAUKEGAN, ILLINOIS.

FRAME FOR PHONOGRAPH-MOTORS.

1,391,717.

Specification of Letters Patent. Patented Sept. 27, 1921.

Application filed April 9, 1920. Serial No. 372,567.

To all whom it may concern:

Be it known that I, GEORGE T. CHERINGTON, a citizen of the United States, residing at Waukegan, county of Lake, and State of Illinois, have invented a certain new and useful Improvement in Frames for Phonograph-Motors, of which the following is a specification.

My invention relates to that class of phonograph motors, in which the motive power is furnished by the springs, and has for its object to provide a frame which will be so constructed that practically all of the operating mechanism is inclosed in a chamber, which is provided with an oil reservoir so that the oil by means of capillary attraction will travel to every part of the operating mechanism.

It is desirable in devices of this character to provide a construction which will enable the manufacturer to use as many driving springs as he desires. With the frames for this purpose with which I am familiar, it requires a different frame for every change in the number of springs.

My invention has for its object to provide a construction in which only a single part needs to be changed in order to change the number of springs employed and this part will not in any way interfere with any of the operative mechanism.

My means of accomplishing the foregoing objects may be more readily understood by having reference to the accompanying drawing, which is hereunto annexed and is a part of this specification, in which:

Figure 1 is a top or plan view of my improved frame.

Fig. 2 is a fragmentary detail view taken on the line 2-2 in Fig. 1.

Similar reference numerals refer to similar parts throughout the entire description.

As shown in the drawings, the frame comprises a rectangular portion 1, one side 2, of which is open and is fitted with a detachable plate 3. At the lower part of this opening is cast or formed a wall 4, which partially closes the opening and forms an oil reservoir or chamber in the bottom part of the rectangular frame. The plate 3, can be drawn tightly against the walls of the chamber by means of screws 5, or any other suitable and convenient means of fastening. If desired, a suitable gasket can be mounted intermediate the wall and the plate, making it oil tight. A plurality of lugs depend

downwardly from the bottom part of the frame. As shown, they are two in number and are indicated by the reference numerals 7 and 8. These lugs are provided with openings, through which extend and in which is mounted a shaft 9, which may be secured to one of the legs by means of a pin 10, or in any other suitable or convenient fashion. This shaft 9, extends laterally from the casing 1, and carries at its outer end an outboard bearing 11, which is detachably secured to the shaft 9, by means of a pin 12. This bearing contains an outwardly extending arm 13, in which may be mounted the spring shaft 14.

It will be apparent from the foregoing description, and from an inspection of the drawings, that I have shown two driving springs, but if a larger number was required, all that would be necessary to do would be to remove the pins 10 and 12, take out the shaft 9, and insert one of the desired length when the outboard bearing 11, can be fitted upon the end of the new shaft, and this is the only change that will need to be made, all of the operating mechanism remaining in the same position that it is in when two or even one spring is employed. I provide an apron or guard for the intermediate gear, and to form bearings for the shaft which carries the said gear. This apron 15, extends laterally from the casing, and is semi cylindrical in shape, and is provided with a flange, which closes the outer end of the semi cylindrical apron, and in which is mounted a bearing for the intermediate shaft, the wall of the casing forming the other bearing.

It will be apparent from the drawings and the description that the movement of the mechanism in the chamber will cause the oil to be thoroughly distributed and it will, as a consequence, travel by capillary action over the entire interior wall of the structure and up and into the bearings, particularly of the turn table shaft and governor control stem, as well as reaching and thoroughly oiling all of the other shafts, which are journaled in the casing, so that by the use of my improved frame, I not only secure improved oiling, but by inclosing the operating parts reduce the noise to a minimum.

I also provide a motor to which can be added as many springs as are desired without changing the operating mechanism in the slightest degree. In some cases it may

be found desirable to employ an electric motor in the place of spring motors, in which case, it can be mounted on the spring shaft, and a pulley can be mounted on the 5 intermediate shaft in the place of the collar 18, which when used with a spring motor holds the shaft in position.

Having described my invention what I 10 regard as new, and desire to secure by Letters Patent is:

1. A frame for phonographs, comprising a rectangular casing, having a chamber therein, open on one side, a wall partially closing said side, a detachable plate covering both said wall and said open side, a plurality of downwardly depending lugs, having openings therethrough, a shaft mounted therein, an outboard bearing mounted on said shaft, a semi cylindrical apron extending laterally from said casing terminating in a flange, and a bearing in said flange.

2. A frame for phonographs, comprising a rectangular casing, having a chamber therein, open on one side, a wall partially closing said side, a detachable plate covering both said wall and said open side, a plurality of downwardly depending lugs, having openings therethrough, a shaft detachably mounted therein, an outboard bearing de-

tachably secured to said shaft, a semi cylindrical apron extending laterally from said casing terminating in a flange, and a bearing in said flange.

3. A frame for phonographs, comprising a rectangular casing, having a chamber therein, open on one side, a wall partially closing said side, a detachable plate covering both said wall and said open side, a plurality of downwardly depending lugs, having openings therethrough, adjustable means carried by the lugs, and an outboard bearing detachably secured thereto.

4. A frame for phonographs, comprising a rectangular casing, the lower rear corner of which is indented, having a chamber 45 therein, open on one side, a wall partially closing said side, a detachable plate covering both said wall and said open side, a plurality of downwardly depending lugs, having openings therethrough, a shaft mounted 50 in said casing, an outboard bearing mounted on said shaft, a semi cylindrical apron extending laterally from said casing, terminating in a flange, and a bearing in said flange.

In testimony whereof, I have signed the 55 foregoing specification.

GEORGE T. CHERINGTON.
